CLAIM

The ornamental design for container panel, as shown and described in the Figures.

DESCRIPTION

FIG. 1 is a perspective view of the container panel;
 FIG. 2 is a front view of the container panel;
 FIG. 3 is a right side view of the container panel; and,
 FIG. 4 is a top view of the container panel.
 The broken line showing of structure is for illustrative purposes only, and forms no part of the claimed design.
